GRAIN SPRING FOR BINDER KNOTTERS

Peter Sutcliffe, Jr., Birtle, Manitoba, Canada

Application September 17, 1943, Serial No. 502,738

2 Claims. (Cl. 56—472)

My invention relates to binder knotters, more particularly having reference to an improved grain spring, being part of the sheaf forming mechanism.

In the art to which the invention relates the grain spring as at present in use in binder knotters does not appear satisfactory and in view of the strain imposed on it is subject to constant breakage and replacement.

The present invention contemplates certain improvements in grain springs for binder knotters by which a more even tension is provided with more life in the action of the spring and practical elimination of breakage.

One of the objects of the invention is accordingly to provide an improved spring of this character more efficient in operation and less subject to breakage than springs at present in use.

A further object of the invention is to provide means for efficiently mounting my improved spring in the knotter to permit the spring to function effectively.

A still further object of the invention is to provide means for attachment of my grain spring in conjunction with the knotter guide rod.

Other features and advantages of the invention will become apparent by reference to the accompanying description taken in conjunction with the drawing wherein like characters of reference indicate like parts throughout the several views and wherein—

Fig. 1 is a top view showing part of a binder knotter assembly and including my improved grain springs.

Fig. 2 is a detail side view of the spring and including the attaching clamp and spring arm.

Fig. 3 is a detail side view of a clamp for attachment of the spring to the knotter shaft or casing.

Fig. 4 shows a section of the binder frame showing attachment of the loop of the spring arm section of the grain spring.

Fig. 5 is a top view of the slide bar and including a section of the knotter shaft and lug with the slide bar in attachment thereto, and further including a fragment of the spring shank.

Fig. 6 shows a top view of the slide bar by itself.

Having reference to the drawing 1 indicates a fragmentary section of the binder frame, 2 generally the knotter shaft and casing substantially parallel to the frame section, and 3 the knotter arms, these parts being standard in binder equipment.

My improved grain spring may be more clearly

understood by reference to Figure 2, and includes a spring section and a spring arm section. The spring section comprises a shank portion 4 with intermediate integral coiled spring 5. The section 4 terminates at one end in a hook member 6 for engagement with the knotter shaft and at the other end in a hook member 7 for engagement with the spring arm section of the grain spring.

The spring arm section of the grain spring is formed of a single piece of material intermediate bent to provide a double loop 8 for engagement of the frame 1 and providing a shank section 9 with eye 10 for engagement of the spring section hook member 7, and a spring arm 11 of conventional design for acting on the sheaf being formed. The spring arm section is attached to the frame 1 by staple 12 engaging one of the loops 8 and inserted through suitable openings in said frame, the ends of the staple being bent as shown in Figure 4. The staple is sufficiently loose to permit the spring arm to turn freely.

For attachment of the spring section to the knotter shaft I provide a collar 13 that encircles 25 the shaft and is held by a cotter pin 14 to which the hook member 6 may engage as more clearly shown in Figure 2. The clamp or collar 13 is loose on the shaft or casing 2.

Additional to the foregoing it was found desirable in the binding of tangled grain to have a somewhat different attachment for the intermediate spring assembly. In this (see Figures 1, 5 and 6), the spring section connects by means of a slide bar 15 to a guide rod 16, the rod 16 being a guide for the grain bundle by the knotter, a fragment only of the rod being shown. On the knotter shaft casing 2 is provided an integral lug 17 with an eye for reception of a bent end 18 of the rod 16, the rod being secured by a cotter pin 19.

The bar 15 includes an eye 20 engageable to slide on the bent end 18 of rod 16 and an eye 21 for engagement of the hook member 6 of the grain spring.

In the use of the device the arrangement as herein provided has proved effective, the spring arm 11 raises with even tension with little chance of breakage and after discharge of the sheaf snaps back with more life than in the present design of spring. The comparatively loose connection provided by staple 12 permits the required amount of play, the double loop 8 preventing side play.

While I have herein described a preferred embodiment of my invention it is obvious that

changes in construction and formation of parts would be permissible, particularly in adaptation of the device to different types of binders, and such changes in so far as they come within the spirit and scope of the appended claims would be considered as part of the present invention.

What I claim and wish to secure by Letters Patent is:

1. In a grain spring for binders, said binder including a knotter shaft and casing and parallel frame section and a guide rod to be carried by said shaft and casing, a spring arm, means pivotally mounting said arm free to turn on the frame section, a spring engaging said arm, and a plate connecting said spring and the knotter shaft and casing through the medium of the

guide rod, the connection between the plate and guide rod permitting a limited endwise movement of the plate.

5 2. In a binder including a knotter shaft and casing and parallel frame section, spring arms each providing a loop and a shank portion, means individually attaching each of said arms free to turn on the frame section, springs engaging the shank portions of the spring arms, means securing said springs to the knotter shaft and casing, and a slide bar included in the securing means of at least one of said springs, said bar being mounted to permit a limited endwise movement thereof.
